Des 809

Samuel F. Pratt of Boston, Mass: Assignor to
W. & J. Treadwell, Perry & Norton, of Albany, N. Y.
Letters Patent No. 809. Dated June 24th 1856.

The schedule referred to in these Letters Patent and making part of the
same.

To whom it may concern:

Be it known that I, Samuel F. Pratt, of the city of
Boston, State of Massachusetts, have produced a new original ^{ornamental} design
for the plates of a parlor cooking stove (called the Bestal Parlor Stove)
and I hereby declare that the annexed drawings forming part of this
specification are full and accurate delineations of the said plates, which
are combined to form the stove, with their ornamented parts. The lower
back plate, lower end plate and upper end plate, being duplicates of
their corresponding plates, and being symmetrically similar in form
and ornament.

What I claim as my production and desire to secure
by Letters Patent is the combination and arrangement of ornamental
forms and figures represented in the accompanying drawings, forming
altogether the ornamental design of a Parlor Cooking Stove
